ATTORNEY.

UNITED STATES PATENT OFFICE.

THEODORE H. SCHMITZ, OF PHILADELPHIA, PENNSYLVANIA.

WINDOW STRUCTURE.

SPECIFICATION forming part of Letters Patent No. 604,868, dated May 31, 1898.

Application filed October 2, 1897. Serial No. 653,816. (No model.)

To all whom it may concern:

Be it known that I, THEODORE H. SCHMITZ, a citizen of the United States, residing in the city and county of Philadelphia and State of Pennsylvania, have invented certain new and useful Improvements in Window Structures, of which the following is a full, clear, and exact description, reference being had to the accompanying drawings, forming a part of this specification.

The object of this invention is to provide a window structure in which the sashes may be slid up and down in the usual manner, in which either or both of the sashes may be turned or set at any desired angle in respect to the window-frame for ventilating or other purposes, and in which either or both of the sashes may be bodily drawn from the frame and be turned or inverted exteriorly thereof for cleaning or other purposes. Incidentally the invention affords simple and efficient means whereby access may be readily had to the interior of the sash-weight boxes and to the weights therein and whereby other advantages are secured.

According to my invention the window-sashes are suspended and counterbalanced within the frame, the stiles and guides for the sashes are bodily movable toward and from the counterweight-boxes, and means are provided for locking said stiles and guides in their positions of adjustment, whereby when the stiles and guides are in their normal position the sashes are supported in the guides in a manner to be vertically movable therein, and whereby when the stiles and guides are in their retracted position the sashes, being unobstructed thereby, may be revolved within the frame or may be bodily withdrawn from the latter and be swung or turned exteriorly thereof. Preferably the weighted sash-cords are attached to pivoted hangers on the sashes, and the lower portions only of the stiles and guides are adjustable, as stated, the upper portions thereof being stationary, as ordinarily.

In the drawings, Figure 1 is an elevation of my improved window structure, parts being broken away for clearness. Fig. 2 is a vertical section, as on the line xx of Fig. 1, showing one of the sashes as withdrawn bodily

from the frame and indicating by dotted lines a sash as revolved or inclined in the frame. Fig. 3 is a transverse section, as on the line yy of Fig. 1. Fig. 4 is a similar section showing the stiles retracted and indicating by dotted lines one of the sashes as being removed from the frame. Fig. 5 is a detail of the sash-hanger and adjuncts. Fig. 6 is a perspective of a part of one of the movable stile-sections with its lock. Fig. 7 is a sectional elevation of a portion of a sash, its counter-weight, and adjuncts. Fig. 8 is a perspective of sash-hanger hereinafter referred to.

A represents the window-frame, provided with the usual boxes a , in which the sash-weights w are contained, and B the stiles, provided with vertical guideways b for the window-sashes C C'. Each of the stiles is preferably constructed in two sections 1 2, each section, with its guides, comprising a single strip provided with parallel longitudinal grooves, whereof the intermediate wall serves as the usual parting-strip, while the side walls perform the function of ordinary beads to keep the sashes in place.

The upper sections are fixed in position to receive and guide the sashes and are provided with the usual pulleys b' for the support and guidance of the sash-cords c , while the lower sections are fitted in the sides of the window-frame to be adjustable toward and from the respective weight-boxes.

In their normal position the lower sections are each in line vertically with the adjacent upper sections, so that the sash-guides of both sections are in alinement to permit the sashes to be slid up and down therein in the usual manner; but in the retracted position the guides are clear of the sashes to permit the latter, when moved below the upper sections, to be turned or inverted within the window-frame or to be drawn bodily therefrom. The lower sections are maintained in the normal position by means of springs d , interposed between them and the opposing walls a' of the weight-boxes, suitable locking means, as E, being employed to maintain the sections in both the normal and retracted positions. In the present instance these locking devices comprise vertical spring-actuated bolts e ,

contained in easings e' , which are mortised in the respective ends of each of the lower sections intermediate the guideways thereof. These bolts, by the action of their springs e^2 , 5 are normally projected beyond the ends of the section, so as to register with appropriate keepers e^3 in the opposing end of the upper section and at the bottom of the window-frame, respectively. Each of the keepers is 10 provided with suitably-located sockets e^4 , with the forward one of which the adjacent bolt engages when the stile is in its normal position and with the other socket when the stile is retracted. The bolts are provided 15 with knobs or projections e^5 , by means of which they may be retracted from the socketed keepers.

The sash-cords are connected with pivoted hangers, as F , on the sides of the respective 20 sashes, so as to facilitate the revolving or turning of the latter under the conditions stated. These hangers comprise angle-plates, the vertical members of which are provided with keyhole-slots f , which may be readily 25 and securely applied to headed pins or screws f' on the sashes, while the horizontal members are perforated to permit the free ends of the sash-cords to be passed therethrough and knotted, as shown. The knots on the cords 30 c cover the enlarged portions of the slots in the hangers and thus obviate any liability of accidental disconnection of the parts. To detach the sashes from the cords, it is merely 35 requisite to draw down the knotted ends of the cords and to slip the hangers from the pivot screws or pins on the sashes. (See Fig. 5.)

It will be seen that when the sashes are 40 bodily swung from and beyond the window-frame the lower stile-sections may be removed from the frame to permit free access to the interior of the sash-weight boxes and to the weights therein, the walls a' of said boxes being appropriately cut away, as at a^2 , Fig. 45 1, for this purpose. It will also be seen that when the sashes are in place, if the bolts be withdrawn from their keepers, the movable stile-sections will press yieldingly against and prevent rattling of the sashes.

50 As illustrated in Fig. 7, I sometimes arrange at the lower end of the weight-box an additional pulley b'' and pass around the same a cord c' , the extremities of which are attached to the lower end of the weight w and to the 55 hanger, respectively, so as to effect a steady and uniform counterbalancing of the sash. The cord c' is preferably provided with a spring-section c'' adjacent to the hanger, so as to maintain the cord taut and insure its 60 engagement with the pulley. In this construction the lower end of the hanger is provided with a slotted lug f''' , into which is slipped the knotted end of the cord, the action of the spring preventing displacement 65 thereof. Preparatory to removing the sash

from the window the lower cords are disengaged from the respective hangers on the sash.

I claim—

1. The combination of devices forming a window structure with a main frame, whereby 70 a pair of window-sashes are suspended and counterbalanced within the frame and adapted to be held therein at any angle of inclination or bodily removed therefrom when desired; said devices consisting of the following 75 elements in combination, namely, a pair of sectional stiles B , B provided with longitudinal guideways b and composed of two separate and independent sections arranged end to end, the upper section being stationary and 80 the lower section bodily adjustable laterally; springs d operating to maintain the lower stile-sections out in normal position to preserve the continuity of the guideways, weight-boxes the walls of which are adapted to furnish one bearing for said springs, locking devices E operating to maintain the lower sections in normal as well as in retracted position, sashes to slide in the guideways, sash-cords and counterweights; said parts being 85 combined, arranged and operating, substantially as described.

2. In a window structure, the combination with a sliding sash, of a hanger consisting of a vertically-movable portion slotted to engage 95 a pin or stud of the sash, and having at each end a projecting slotted lug, a counterbalance-weight, a cord connected at one end to said weight and at the other end to the upper of said lugs, and a second cord connected at one 100 end to the opposite end of the said weight, and to the lower lug of said hanger, said second cord having a portion of its length constituted by a spring, substantially as specified.

105 3. In a window structure, the combination with the main frame, of adjustable stile-sections therin, provided with longitudinal guideways, means to maintain the stiles in and out of normal position, sashes to slide in 110 the guideways, and angular hangers F for the sash-cords, pivoted to supports on the sashes, said hangers being constructed with a slotted vertical member, and with opposite horizontal members, perforated for the passage of 115 sash-cords, the knots of which are inclosed in the hangers; and counterweights on the opposite ends of the sash-cords; substantially as described.

120 4. The combination, forming a window structure, with a main frame, sectional stiles arranged end to end, the upper section being stationary and the lower section being adjustable laterally, vertical guideways therein for the sashes, weight-boxes having walls a' recessed at a^2 to permit access thereto, springs d interposed between the lower stile-sections and the walls of the weight-boxes, and locking devices consisting of normally-projecting 125 spring-actuated bolts e , casings therefor in 130

the ends of the lower section, and keepers e^3 mounted in the opposing end of the upper section, with sockets e^4 adapted to engage the said bolts; said elements being combined and 5 operating substantially as and for the purposes set forth.

In testimony whereof I have hereunto af-

fixed my signature this 28th day of September, A. D. 1897.

THEODORE H. SCHMITZ.
